UNITED STATES PATENT OFFICE

EDWARD T. ADAMS, OF PHOENIX, ARIZONA, ASSIGNOR TO FAIRBANKS, MORSE & CO.,
OF CHICAGO, ILLINOIS, A CORPORATION OF ILLINOIS

INJECTION PUMP

Application filed October 20, 1928. Serial No. 313,864.

This invention relates to improvements in injection pumps, and particularly to improved means for altering the displacement stroke of injection pumps for internal combustion engines.

An object of this invention is the provision of an improved assembly in which the parts are few in number, and of simple, rugged construction.

10 A further object is the provision of means for regulating the length of the plunger stroke, and hence the quantity of oil delivered, through a simple linkage arrangement adapted for control by a governor or the like, 15 and whereby the amount of fuel delivered to the engine, is controlled by the effective length of the injection pump plunger stroke, rather than by the more usual regulation of the closing of the pump suction valves.

20 Further objects are to provide a construction, in which better regulation of the fuel injection is maintained throughout the operating range of the engine; an improved construction in which the tendency for the 25 engine speed to fluctuate unduly, following changes in load, is minimized.

Further objects and advantages will appear from the following detailed description of parts and the accompanying drawings, 30 in which Fig. 1 is a sectional elevation through the pump housing of an engine, to which a preferred form of the invention is applied; Fig. 2 shows a partial section through an assembly of injection pumps, taken along the line 2—2 of Fig. 1.

It will, of course, be understood that the drawings and the following description relate only to a single preferred executional embodiment of the present invention, and that 40 substantial alterations in the construction and arrangement of the parts may be made without departing from the spirit and full scope of the invention.

45 Referring by numerals to the drawings, the injection pump body 1 may contain any number of pumps, the number of which will depend upon the number of engine power cylinders. The pump barrel 2 may be formed in- 50 tegrally with the pump body, or may be made

removable, in which case, a nut 3 is provided to hold the removable barrel in position. Operatively associated with the pump barrel 2, is a pump plunger 4 which may be formed with a cup-shape extension 5 for a purpose 55 that will hereinafter appear. Positioned between the back of the extension 5 and the nut 3, is a plunger spring 6 serving to urge plunger 4 to its lower position. A plunger stop 7 may be threaded in a portion of the cylinder, and may be arranged to provide a certain amount of adjustability for the stroke of plunger 4, by means of the insertion or removal of shims 8 which will raise or lower the stop 7 sufficiently to limit the downward 60 travel of the plunger, which provision may result in a clearance between the plunger 4 and a crosshead 9. One end of the crosshead is adapted to be positioned by a guide 10, formed in the nut 7, while the opposite end 11 of the crosshead 9 is slidably guided in a barrel 12 formed as part of a casing 13.

The inner wall of the crosshead forms a socket 14, in which resides a ball end 15 of the pushrod 16, and permits the opposite end 17 of the rod to move freely along an arcuate path, for purposes of adjustment of the pump stroke, as will appear hereinafter. An eccentric strap 18 is pivotally connected to the pushrod 16, by means of a pin 19, or the equivalent, and is rotatably mounted on a governor controlled eccentric 20, preferably of tubular form, which is eccentrically mounted on the governor shaft 21, as a fixed center. It will be readily seen that the eccentric 20 has an incomplete rotational movement in either direction, which is transmitted through the strap and related parts, to the pushrod 16, to move the rod to the right or left of its central position, and thus to effect 80 an angular adjustment between the paths of travel of the pushrod and plunger. The rotational movement of the eccentric may be controlled by an engine governor of any suitable form (not shown), connected in automatic adjusting relation to the shaft 21.

The end 17 of the pushrod 16 is adapted to be freely and adjustably moved along an arc corresponding to the arcuate shape of upper 90 surface 22, on the rocker arm 23. This sur-

face is preferably in the form of a part cylinder, having a radius corresponding substantially to the length of the pushrod 16. The rocker arm 23 is pivotally mounted on a fixed pin 24. As will be seen from Fig. 1, the surface 22 extends across and on each side of the pivot 24, for reasons which will later appear. The rocker is, by preference, provided with a tappet roller 25, mounted on a pin 26 in a bifurcated portion of the rocker arm 23. The roller is kept in contact with an injection cam 27, mounted on the cam shaft 28, which is driven in timed relation with the crank shaft, (not shown), of the engine. The high point or nose 29 of the cam 27 is adapted to give the roller 25 and its related rocker arm 23, the required reciprocating movement to operate the injection pump plunger.

Referring again to the pump body 1, the oil supply reservoir is connected to the pump body by the passage 30. The pump chamber, shown at 31, is provided with a spring loaded suction valve 32, located in communication with the supply passage 30. A spring loaded discharge valve 33, controls an outlet passage for the fuel, into the discharge line 34 leading to the injector.

It will be understood that the cam shaft 28 rotates in timed relation with the crank shaft 30 of the engine, and may serve to actuate one or any number of the cams 27, corresponding to the number of power cylinders in the engine. As the nose of the cam 27 passes under the roller 25, the rocker arm 23 is partially rotated about its fixed pivot 24, transmitting a reciprocating movement to the pushrod 16, and hence to the pump plunger 4. As the high point 29 passes beyond the roller, the pump plunger 4 is urged downwardly in the barrel 2, by spring 6, thus causing a suction in the pump chamber 31. At this time the suction valve 32 opens, and fuel is drawn into the pump chamber. As the high point 29 of the cam 27 again comes into contact with the roller 25, the rocker 23 is raised and impels upwardly the pushrod 16 and the plunger 4, the displacement of which results in a pressure in the pump chamber 31, closing the suction valve 32 and opening the discharge valve 33, through which the fuel is driven under pressure into the injector.

It will readily be seen that the amount of fuel injected into the cylinder depends upon the length of the pump stroke, and further, that the amount of fuel required depends on load conditions. As long as the load remains constant, the governor maintains a fixed contact position of the end 17 of the pushrod with respect to the surface 22 of the rocker arm 23. As the load increases, the governor rotates the shaft 21 in an anti-clockwise direction, (as seen in Fig. 1), which moves the lower end of the pushrod to the right, thereby increasing the stroke of the pump and the amount of fuel dis-

placed and injected, in accordance with the load. As the load becomes less, the governor is arranged to rotate the shaft 21 in a clockwise direction (Fig. 1), which, through the eccentric and strap 18, moves the lower end 17 of the pushrod to the left, thereby shortening the stroke of the pump and decreasing the amount of fuel injected into the cylinder. By moving the lower end of the pushrod far enough to the left, the stroke of the pump may be reduced to zero, and all the fuel cut off, so as to stop the engine.

One feature of the invention is found in a provision for minimizing the drag or frictional resistance that the governor must otherwise overcome in moving the end 17 of the pushrod over the surface 22 of the rocker 23. The member 7 may, by means of shims 8, be raised sufficiently to serve as a stop, acting against the lower face of the plunger to limit its downward travel, thus providing a slight clearance between the lower end 17 of the pushrod and the rocker 23 when the roller 22 is following the low portions of cam 27. This clearance removes the spring pressure from these parts, and reduces the friction which must otherwise be overcome in moving the push rod across the face of the rocker when the governor is changing the stroke of the pump.

The assembly described will be seen to provide a compact, rugged means of controlling fuel injection, in fulfillment of each of the objects of the invention as set forth above. Besides the advantages and economies afforded by a construction in accordance with this invention, when used with a suitable governor, the described device shows a quick and positive response to speed fluctuations and provides for a remarkably close speed regulation over the entire range of engine speeds.

I claim as my invention:

1. In an assembly including an injection pump and a pushrod actuated mechanism therefor, an actuating cam, a pump plunger arranged to be actuated in one direction responsive to rotation of said cam, a spring arranged to actuate the plunger in the opposite direction, a rocker operated by the cam, a pushrod mounted for swinging movement with respect to said rocker, and operatively associating said pump plunger and cam, a crosshead pivotally engaging the pushrod, and a threaded stop for said plunger, forming a guiding member for said crosshead, said rocker having a fixed pivot and an arcuate pushrod seat extending across and on each side of said pivot.

2. In an injection pump operating mechanism, a cam, a cam actuated rocker, having a curved pushrod seat extending across its axis, a spring pressed plunger arranged to be actuated by said mechanism, a pushrod operatively associating said plunger and

rocker, a crosshead having a socket for receiving one end of the pushrod, and an extension engaging said plunger, an eccentric adapted to be rotated for adjusting the angular relation between the paths of travel of said plunger and pushrod, and an adjustable stop for the plunger, constituting a guide for the crosshead extension, and adapted to relieve spring resistance against rotational movement of said eccentric.

3. In an injection pump assembly for an internal combustion engine, a pump operating cam adapted to be rotated in timed relation with the engine, a tappet adapted to operate on said cam and having a fixed pivot, and a concave rod-receiving surface extending on each side of said pivot, a push-rod adapted to be reciprocated under the influence of said cam and said tappet, a pump barrel, a spring-pressed plunger operatively disposed therein, a crosshead distinct from the pump plunger, serving as an operative connection between said pushrod and said plunger, said pushrod being disposed in swingable relation to said crosshead and having a ball and socket connection therewith, a guide for said crosshead, including two threadedly connected portions, one of said portions arranged for rotation relative to the other portion to constitute an adjustable stop for the spring-urged movement of the plunger whereby to permit free swinging movement of said pushrod, and means for varying the angular relation between said pushrod and said plunger; said means comprising an eccentric, an eccentric shaft, and an eccentric strap pivotally connected to said pushrod, said last named means being adapted upon said variation of angular relation to control and terminate delivery of fuel by said pump by effecting variation in the stroke of said plunger.
